UNITED STATES PATENT OFFICE.

LUCIEN GÉNARD, OF OYONNAX, FRANCE, ASSIGNOR TO H. D. THURGAR LIMITED, OF LONDON, ENGLAND, A CORPORATION OF GREAT BRITAIN.

DESIGN FOR A COMBINED HAIR SLIDE AND POSTICHE HOLDER.

Application filed March 27, 1929, Serial No. 30,644, and in Great Britain November 26, 1928. Term of patent 14 years.

To all whom it may concern:

Be it known that I, LUCIEN GÉNARD, a citizen of the French Republic, residing at Oyonnax, Aisne, France, have invented a new, original, and ornamental Design for a Combined Hair Slide and Postiche Holder, of which the following is a specification, reference being had to the accompanying drawing, forming part thereof.

The figure is a perspective view of a combined hair slide and postiche holder, showing my new design.

I claim:

The ornamental design for a combined hair slide and postiche holder, as shown.

LUCIEN GÉNARD.
